UNITED STATES PATENT OFFICE

JAMES C. SMITH, OF SAN FRANCISCO, CALIFORNIA

CHRISTMAS-TREE HOLDER

Application filed December 31, 1927. Serial No. 243,997.

The invention relates to a Christmas tree holder. or sacrificing any of the advantages of the invention.

The object of the present invention is to improve the construction of Christmas tree holders and to provide a simple, practical and efficient Christmas tree holder adapted to be easily, cheaply and rapidly constructed and capable also of being employed as a flower stand or jardinière, thereby enabling 10 the device to be used throughout the entire year.

A further object of the invention is to provide a Christmas tree holder of this character adapted to be constructed of concrete 15 or similar plastic material and capable of being readily molded in a large variety of sizes and designs so as to present the designs of ornamental appearance and at the same time have the required weight so as to securely hold the Christmas tree in an upright position and positively prevent the same from falling over.

It is also an object of the invention to equip the Christmas tree holder with adjustable 25 clamping means adapted to accommodate and engage a pole, or the trunks of Christmas trees of different diameters or sizes and capable of stiffening and clamping the trunk of the Christmas tree above the body portion 30 of the holder to increase the effectiveness of the device, and removable from the body portion of the Christmas tree holder to permit the body portion to be advantageously employed as a flower stand or jardinière.

Another object of the invention is to provide means for receiving and holding water and to enable water to be conveniently poured into the holder without danger of flowing over the upper edges of the walls on to the 40 exterior of Christmas tree holder.

With these and other objects in view, the invention consists in the construction and novel combination and arrangement of parts hereinafter fully described, illustrated in the 45 accompanying drawings and pointed out in the claims hereto appended, it being understood that various changes in the form, proportion and minor details of construction, within the scope of the claims, may be resorted to without departing from the spirit

In the drawings:—

Figure 1 is a vertical sectional view of a Christmas tree holder constructed in accordance with this invention. 55

Fig. 2 is a plan view of the same.

Fig. 3 is a vertical sectional view of another form of the invention in which the tree receiving opening is provided with straight vertical walls. 60

Fig. 4 is a vertical sectional view of another form of the invention in which springs are employed for yieldably engaging the trunk of a Christmas tree to permit tree trunks 65 of different diameters to be gripped in the holder.

Fig. 5 is a vertical sectional view illustrating a form of the invention in which the plastic body is equipped with casters and is 70 provided with means for holding the tree against vertical movement.

Fig. 6 is a horizontal sectional view on the line 6—6 of Fig. 5.

Fig. 7 is a detail sectional view illustrating the arrangement of the removable fastening device for holding the tree against vertical movement in the plastic body. 75

In the accompanying drawings in which are illustrated the preferred embodiments 80 of the invention, the Christmas tree holder comprises in its construction a body 1 of concrete or other plastic material adapted to be molded in various shapes and designs. The body which may be varied in size to provide 85 the desired weight is provided with a central vertical Christmas tree receiving opening 2 which in the form of the invention illustrated in Figs. 1 and 2 of the drawing has a general downward taper, but a vertical opening 90 having vertical walls 3 may be employed as illustrated in Fig. 3 of the drawings. Also, as shown in Fig. 4, the upper portion of the tree receiving opening may be provided with vertical walls 4 and a lower portion with inclined walls 5, thereby providing an opening having a tapered lower portion. The exterior of the body 1, may be round, square, hexagonal or any other desired configuration 95 and may have any preferred character of or- 100

namentation. The bottom of the body is provided with a recess 6 communicating with and forming an enlargement of the vertical opening 1 and adapted to receive a pan 7 or other receptacle for holding water. The water pan 7 is of greater diameter than the lower end of the vertical opening 1 so that water poured into the upper end of the opening will flow into the pan and in order to enable water to be conveniently supplied to the Christmas tree holder without liability of flowing over the upper edges of the same, the body portion is provided at the upper edge with a projecting bead 8 preferably located adjacent the outer face of the Christmas tree holder and forming a ridge around the same. This will assist in preventing water from spilling upon the floor or other supporting surface.

20 The trunk 9 of a Christmas tree is securely held in the holder by means of a plurality of wedges 10 which may be of any preferred number and which are adjustably mounted in grooves or recesses 11 in the walls of the tree receiving opening. The grooves or recesses extend longitudinally of the tree receiving opening preferably from the upper to the lower end of the same and they have inclined rear walls and side walls which are preferably arranged in parallel vertical planes. The inclined rear walls of the recesses receive the inclined edges of the wedges 10 which have vertical inner edges to engage the tree 9 and inclined outer edges to fit 35 against the inclined walls or faces of the body 1. The wedges are adjustable vertically to vary the diameter of the device to suit the size of the trunk of a Christmas tree and they extend a considerable distance above the upper edge of the holder to lengthen the device and enable the same to stiffen a Christmas tree and increase the effectiveness of the clamping means. The wedges are preferably provided at their upper ends with heads 40 45 50 55 60 65 70 75 80 85 90 95 100 105 110 115 120 125 130

Instead of employing wedges for adjustably gripping the trunk of a Christman tree, a pole or the like, the Christmas tree holder

may, as illustrated in Fig. 4 of the drawings, be provided with a plurality of bowed springs 14 of approximately semi-circular shape having partially coiled terminals 15 and arranged in vertical recesses 16 in the upper portion of the tree receiving opening of the plastic body. The partially coiled approximately hook-shaped terminals of the bowed springs 14 present convex faces to the rear walls of the longitudinal recesses 16 and the springs which may be of any desired number are adapted to be compressed by the trunk of a Christmas tree and they automatically conform to the configuration of the same and will firmly hold a Christmas tree in an upright position. The springs 14 are removable from the recesses 16 and both may be provided at the upper and lower ends of the recesses with pins 17 embedded in the plastic material when the same is molded to form the body. The pins extend across the rear portions of the recesses and are arranged in spaced relation with the rear and end walls of the same so that the springs may be rigidly engaged with and disengaged from the same by flexing the partially coiled or hook shaped terminals of the springs.

The molded plastic material may be painted or otherwise finished exteriorly and by being molded of concrete or similar material they may be rapidly manufactured at a very low cost.

In Figs. 5 to 7 inclusive, is illustrated a form of the invention in which the plastic base is equipped with casters 18 arranged in extensions 19 of the pan receiving recess. The casters which may be three or more in number are of any desired construction and their socket members 20 are embedded in the plastic material of the body and are provided with flanges 21 which are fitted against the horizontal top wall of the extension 19 of the bottom pan receiving recess. The casters will enable the Christmas tree holder with a Christmas tree to be readily moved over the floor of the supporting surface without scratching or otherwise marring the same or injuring the carpet or other floor covering.

The vertical opening in the body shown in Fig. 5 has a tapered upper main portion 22 and a tapered lower portion 23, the walls of the tapered lower portion being arranged at an angle to the walls of the tapered upper portion. The upper portion 22 of the opening which is adapted to receive a tree holder or the like is provided with grooves 24 similar to those heretofore described and receiving wedges 26 which are arranged in the said grooves and which engage and clamp the tree or pole 27. The tree or pole 27 is provided with a tapered lower portion 28 to fit the lower tapered portion of the opening in the plastic body and in order to prevent relative upward movement of the tree or pole and a consequent loosening of the wedges, the plas-

tic body is provided with a transversely disposed bore or hole 29 through which extends a nail 30 or other suitable fastening device provided at its outer end with a head and having its inner pointed end embedded in the tree or pole. One or more nails may be employed and by securing the pole or tree against vertical movement in the opening of the body the wedges are prevented from being accidentally loosened by lifting the tree in the holder. The plastic bodies shown in Figs. 1 to 4 inclusive are also provided with inclined bores or holes 29 for the reception of a nail or other suitable fastening device for locking the tree or pole in the holder. While the bore or hole 29 is shown at a slight inclination, it may be arranged in any other suitable position such as horizontally, and the nail or other fastening device may be readily withdrawn when it is desired to remove the tree or pole from the holder. The holder in addition to being employed for supporting Christmas trees may be advantageously employed as a flag pole holder or for holding any other analogous decoration or a pole for any purpose.

What is claimed is:—

1. A Christmas tree holder comprising a body portion of molded plastic material provided with a vertical Christmas tree receiving opening and having longitudinal recesses in the walls of the opening, and a plurality of wedges slidably mounted in the said recesses and adapted to engage Christmas trees of different diameters, and provided intermediate of their ends with a recess having upper and lower walls and adapted to permit expansion of a Christmas tree within the same.
- 40 2. A Christmas tree holder comprising a body provided with a vertical opening adapted to receive a tree or pole, said body being also provided in the walls of the opening with a plurality of longitudinal recesses and having a bore or opening, a plurality of adjustable clamping means mounted in the said recesses for engaging the tree or pole, and a fastening device arranged in the bore or hole and extending into the vertical opening for engaging the tree or pole to prevent relative movement of the same and a loosening of the means.
- 45 3. A self-supporting Christmas tree holder comprising a single piece body of molded plastic material enlarged at the bottom to form a base of sufficient size to support the holder and a Christmas tree in an upright position and having a vertical opening of sufficient diameter to receive Christmas trees of different sizes, the walls of the vertical opening being provided with relatively narrow longitudinal grooves and a plurality of relatively thin wedges operating in the grooves and adapted to grip Christmas trees of different sizes and shapes, whereby the

base may be clamped to a Christmas tree in position for supporting the Christmas tree in a vertical position.

In testimony whereof, I have hereunto set my hand.

JAMES C. SMITH.
